(57) **CLAIM**

The ornamental design for a tire, as shown and described.

DESCRIPTION

FIG. 1 is a perspective view of a tire showing my present design;

FIG. 2 is a front view thereof;

FIG. 3 is a left side view thereof;

FIG. 4 is an enlarged view of the portion designated as "4" in FIG. 1;

FIG. 5 is an enlarged view of the portion designated as "5" in FIG. 4;

FIG. 6 is an enlarged view of the portion designated as "6" in FIG. 2;

FIG. 7 is an enlarged view of the portion designated as "T" in FIG. 3;

FIG. 8 is an enlarged view of the portion designated as "8" in FIG. 6, and,

FIG. 9 is an enlarged perspective view taken along the section line 9-9 of FIG. 2.

A rear view of the tire is omitted because it is a mirror image of the front view thereof.

A right side view of the tire is omitted because it is a mirror image of the left side view thereof.

A top plan view and a bottom plan view of the tire are omitted because they are the same as the front view thereof.
